UNITED STATES PATENT OFFICE.

JACOB V. DYRR, OF BELL, CALIFORNIA.

COLLAPSIBLE CAMP BED.

Application filed June 25, 1921. Serial No. 480,278.

To all whom it may concern:

Be it known that I, JACOB V. DYRR, a citizen of the United States, residing at Bell, in the county of Los Angeles and State of California, have invented a new and useful Collapsible Camp Bed, of which the following is a specification.

An object of the invention is to provide a simple bed which is easily collapsible into a compact form for storage and transportation.

Another object is to provide for powerful leverage easily applied in the operation of setting up the bed, whereby the bed bottom will be drawn taut and all of the parts including detachable legs will be held together with perfect rigidity within the requirements of the art.

The invention comprises the combination with a spring bed bottom, of a frame, members of which are hinged together by hinges having the axes of their pivots at right angles to the plane of the bed bottom and arranged on the inner sides of said members so that the members can be bent outward in the operation of collapsing the frame, and forced back from the outwardly bent position to the straight position with practical ease in setting up the frame; and by this construction it is possible to utilize the spring bed bottom as a purchase to assist in applying toggle joint leverage to the work of stretching the spring bed bottom, and putting it under tension.

Another feature of the invention is the use of the supporting legs to pivot together the rigid and the toggle jointed members of the frame so that when the members which are jointed between their ends are brought into extended position to stretch the bed bottom, the action of the springs of the bed bottom tend to draw opposite members of the frame toward each other to cooperate with the leverage of the jointed frame members so as to clamp the legs in place and to give absolute rigidity to the legs as well as to the frame when the frame is stretched.

Another object is to provide a combined metal and wood collapsible frame of great strength and lightness.

Other objects, advantages and features of invention may appear from the accompanying drawing, the subjoined detail description and the appended claims.

The accompanying drawing illustrates the invention.

Figure 1 is a broken plan of an erected camp bed constructed in accordance with this invention. Parts of one of the jointed frame members are shown in horizontal section on line x^1-x^1 , Fig. 2.

Fig. 2 is a fragmental elevation in section on irregular line x^2-x^2 , Fig. 1.

Fig. 3 is a reduced plan of the camp bed shown in Fig. 1. Dotted lines indicate a position of parts during the operation of bringing the collapsible camp bed to the set-up form.

Fig. 4 is a top view of one of the side frame members collapsed.

Fig. 5 is a fragmental view of a modified form of the camp bed.

Fig. 6 is a perspective view of one of the toggle joint hinges.

Fig. 7 is an end view of one of the side members.

Preferably the jointed members are each constructed with two wooden bars of equal length; making four of such bars to each bed frame.

It is understood that any suitable material and any appropriate dimensions may be used in the construction of this invention and that the materials therein specified are those that are preferred.

The collapsible rectangular bed frame 1 consists of the pairs of members comprising end plates 2, 3, and knuckle jointed side members 4, 5, that are pivotally connected at the corners of frame 1 by cylindrical posts or legs 6.

The end plates 2, 3 are provided with flanges 7, 8 between which the ends of jointed members 4, 5 are adapted to fit; and through the flanges 7, 8 are holes 9 that are adapted to register with holes 10 through the ends of jointed members 4, 5; and the legs 6 are made a sliding fit through holes 9, 10 to pivotally connect the frame members together.

Legs 6 are provided with cotter pins or supports 11 at a predetermined height that temporarily hold the bed frame 1 up in a horizontal plane while the bed is in course of erection. To this end the respective ends of members 2, 3 and 4, 5 are placed together and the top ends of the four legs inserted from the underside of the registering holes 9, 10 until the cotter pins or stops 11 contact with the bottom flanges 8 of end plates 2, 3 whereby the frame is supported until the erection of the bed is com-

pleted, and in this position the parts 12, 13 of the side members 4, 5 are angling toward one another as shown by dotted lines in Fig. 3.

5 A flexible bed bottom 14 is attached to end plates 2, 3 and is adapted to be collapsed into a bundle between these ends when the bed is dismounted. The bottom 14 preferably is wire fabric that has its ends 10 provided with springs 15 that are connected to flanges 7 of ends 2, 3.

Parts 12, 13 are connected by hinge members 16, 17 with bearing pins 18 that are secured by rivets 19 to their respective parts.

15 The hinge members 16 have elongated flanges 20 that are connected by a web and adapted to partly enclose the hinged ends of parts 13 when they are in alignment with parts 12; and the flanges 20 have holes 20 adapted to register with similar holes in the hinged ends of 13 and to receive cotter pins 21 that when in place hold parts 12 and 13 in alignment or in extended position and the web portion 22 of extension 20 are stops 25 that prevent the pairs of jointed members 4, 5 from being moved inward farther than to a fully extended position.

When the bed is to be erected, the bottom 14 is unrolled and ends 2, 3 spread apart as 30 much as can be done by hand. Then the jointed member 4, 5 are placed in position as hereinbefore described and legs 6 inserted in place, which will position the frame 1 as shown by dotted lines in Fig. 3. Then

35 pressure is applied to the joints of members 4, 5 to move them from the dotted to the full line position shown in Fig. 3 which stretches the bed bottom 14 and applies considerable tension to spring 15. Also this 40 toggle movement of the jointed members 4, 5 causes clasping or binding pressure to be applied to the bed legs 6 in a direction opposite to the pull applied by springs 15 on the ends 2, 3 so that the legs 6 are firmly 45 clamped between the flanges of ends 2, 3 and the ends of the jointed members 4, 5; and this clamping of legs 6 is so great that the full weight of the bed and occupants is supported independently of the cotter pins 11.

50 The bed can be constructed of any material and finished as desired. Preferably I construct my end plates of angle irons to which short angle plates are secured to form the lower flanges 8 that parallel flanges 7.

55 The jointed side members 4, 5 are preferably formed of wooden parts 12, 13 that have sockets 23 riveted to their ends, so that the legs 6 are pinched between metallic surfaces when the bed is assembled.

60 A modified form of constructing and connecting the frame members 2, 3 and 4, 5 is shown in Fig. 5. The ends of the side members are slotted at 24 to receive the flanges 7 of end members 2, 3. The pivotal connection and pressure applied to hold the pivot

in place is substantially the same as hereinbefore described.

The parts are collapsed and disconnected by removing the cotter pins 21 and then moving the hinged side members 4, 5 from a fully extended position indicated by full lines in Fig. 3, to the dotted line or collapsed position shown therein; which removes tension from the bed bottom 14 and releases the pinching or clasping pressure on 75 legs 6 so that they can be removed to separate the ends of the end and side members 2, 3, 4, 5.

Then the hinged side members are folded as shown in Fig. 4 after which the bed bottom 14 is folded between end members 2, 3. Then the parts can all be assembled into a single compact bundle.

The invention is broadly new, basic and pioneer in that the frame is constructed with jointed rails or side members which bend outwardly sidewise relative to the frame in the collapsing operation and are pushed in sidewise in the operation of setting up the bed; and the top and bottom of each bar of the jointed members is encased at one end by the hinge member which is fixed to one of said bars. In this way I make it possible for the person setting up the bed to utilize the partially stretched bed bottom as a purchase 95 to enable him to easily operate the toggle joint for giving tension to the spring bed bottom, but I also secure great rigidity of frame and hold the jointed members rigidly; and the bed can only be collapsed by the 100 application of considerable force sidewise to spread the knuckle joints apart. The amount of such force will depend upon the tension placed upon the springs.

In setting up the bed having the spring 105 bed bottom fixed to the members 2, 3, and the legs inserted as shown in Fig. 2, the operator will first bring one of the side members into the straight position. This is easily done because the end members 2, being 110 oblique to the side member that has been straightened, leave the bed bottom free from tension. The operator then standing outside the outwardly bent members may take hold of the bed bottom near the middle 115 thereof and this gives him a purchase to sustain the strain of forcing the outwardly bent side member into straight position.

An advantage of having the hinge member bearing pin 18 on the inside of the side 120 members 4 and 5 is that it will not be necessary to reach underneath the bed bottom 14 when erecting the bed.

An advantage of having the legs 6 detachably connecting the side and end frames of 125 the bed is that a very compact bundle is obtained when the bed is in collapsed position.

A further advantage of having the legs 6 detachably and pivotally connecting the 130

side and end frames of the bed is cheapness of construction, ease of assembling and manufacture.

I claim:

- 5 1. In a collapsible bed having pairs of end and side frame members and a spring bed bottom having its opposite ends connected to the end pair of said frame members; detachable legs forming a pivotal connection
- 10 between the ends of the pairs of end and side frame members; and hinges interposed in the pair of side frame members; said hinges being arranged to extend said side members and clamp the legs in place when
- 15 the end and side frame members are pivotally connected and when said hinges are moved toward one another.
- 20 2. In a collapsible bed having a pair of side and a pair of end frame members and a spring bed bottom with opposite ends connected to said pair of end frame members, legs detachably and pivotally connecting the ends of said pairs of end and side frame members, hinges interposed in said side
- 25 frame members and arranged to extend said side frame members to apply tension to said spring bed bottom and pressure on said legs to hold them in place when the hinged portions of said end are moved toward one
- 30 another, means for limiting the movement of said hinges toward one another when the ends of said end and side frame members are pivotally connected, and means for holding said side frame members in extended position when said hinges have reached the limit of movement toward one another.
- 35 3. In a collapsible bed having a pair of side and a pair of end frame members and a spring bed bottom with opposite ends connected to said pair of end frame members, legs detachably connecting the ends of the end and side frame members; said legs form-

ing pivots between said side and end frame members; hinges interposed in said side members and arranged so that said side 45 members have a toggle movement relative to the end frame members to extend said side frame members and apply tension to the spring bed bottom and to clasp or pinch the leg pivots; webbed stops connected with 50 said hinges to limit their movement in one direction, and means for holding said side frame members in extended position when they have been moved to apply tension to the spring bed bottom and pinch or clasp 55 said legs.

4. In combination with a spring bed bottom, two frame members fastened to the spring bed bottom; two toggle jointed members pivoted to the first named members by 60 legs projecting from one side of said frame so that the tension put upon the spring bed bottom by extending the jointed members will clamp the legs in place.

5. In a collapsible bed having a pair of 65 end frame members and a spring bed bottom with opposite ends connected to said members; a pair of side frame members; legs detachably and pivotally connecting the ends of said pair of side frame members to the 70 ends of said pair of end frame members and provided with stops to support said pairs of members; and hinges interposed in said pair of side frame members and arranged to extend said side frame members to apply tension to said spring bed bottom and to clamp 75 said legs in position.

In testimony whereof, I have hereunto set my hand at Los Angeles, California, this 17th day of June, 1921.

JACOB V. DYRR.
